Primary Examiner — Marianne Pandozzi*(74) Attorney, Agent, or Firm* — Dave Alan Lingbeck(57) **CLAIM**

The ornamental design for a foldable surface protector, as shown and described.

DESCRIPTION

FIG. 1 is top perspective view of the foldable surface protector showing our new design.

FIG. 2 is a bottom perspective view of the foldable surface protector.

FIG. 3 is a front elevation view of the foldable surface protector.

FIG. 4 is a back elevation view of the foldable surface protector.

FIG. 5 is a side elevation view of the foldable surface protector.

FIG. 6 is a bottom perspective view of the foldable surface protector in a folded position; and,

FIG. 7 is a top perspective view of the foldable surface protector in a folded position.
